COIN WRAPPING AND COUNTING MACHINE

Sam K. Iverson, Colfax, Wis.

Application October 18, 1948, Serial No. 55,189

1 Claim. (Cl. 53—46)

1

This invention relates to a device for counting and wrapping coins.

It is necessary in practically every business to count coins of various denominations, assemble them in predetermined amounts, and wrap them. An overwhelming majority of businesses are small, and since the small business man cannot afford expensive machinery for this purpose, the work is in most cases done by hand. The work is time consuming and laborious. Additionally, the human tendency to err results quite often in an inaccurate account.

An important object of the present invention, accordingly, is the provision of a device as described that will be capable of manufacture at a cost low enough to place it within reach of all those having need for it.

Another important object is to provide a device as described so designed as to be practically incapable of getting out-of-order, and so designed, further, as to require no maintenance.

Another important object is to provide a device as described which will be accurate in the counting of coins.

Another important object is to provide a device as described that can be used with speed and ease both in the counting and the wrapping of coins.

To this end, my invention briefly includes a base that supports all the other parts of the invention, which base is shallowly grooved to receive a roll of coins, whether they be dimes, nickels, pennies, quarters, or half dollars; sleeve-like casings fixedly mounted on the base at opposite ends of the groove; opposed bolts adapted to engage opposite ends of a roll of coins placed in the groove, that are spring-pressed out of the casing; and means for adjusting the relation of the bolts to each other, so as to accommodate the machine to the counting and wrapping of coins of different denominations.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings:

Figure 1 is a side elevational view of a device constructed in accordance with the invention.

Figure 2 is a top plan view.

Figure 3 is an enlarged end elevation.

2

Figure 4 is an enlarged section taken on line 4—4 of Fig. 2.

Figure 5 is a section similar to Fig. 4, showing a modification.

5 Referring to the drawings in detail, 10 is a base of generally elongated and rectangular conformation, and constructed of any suitable material, such as metal, wood, or plastic.

10 Centrally disposed in the base, and formed in the upper surface thereof, is an elongated and shallow groove 11, that is curved transversely from end to end, said transverse curvature being best illustrated in Figure 3. This groove is for receiving a roll of coins A to be counted and wrapped.

15 Adjacent each end of the groove 11, and aligned longitudinally with the groove, are the hold-down clamps 12, of inverted U-shape in cross section, and fixedly secured to the upper surface of the base by any suitable fastening means. These 20 clamps respectively hold fixedly to the base the sleeve-like casing 13, there being one such casing at either end of the device.

The casings 13 in the present instance are cylindrical, and tubular, and each casing is open 25 at both ends. Communicating with the bore of each casing 13 is the elongated closed slot 14 formed in the wall of the casing, and aligned longitudinally therewith.

Opening from each slot 14 are the spaced lateral notches 15, 16, 17, 18. The purpose and use 30 of these notches will be set forth in detail hereinafter. For the present, it is sufficient to state that the notches are used in connection with adjusting of the device to count coins of different 35 denominations. In the illustrated example of the device, notch 15 is used for counting five dollars in dimes; 16 is used for counting ten dollars in quarters; 17 is used for two dollars in nickels; and 18 is used for fifty cents in pennies.

40 Slidable in the casings 13 are the sleeves 19. Each sleeve is formed with the bore 20 opening at opposite ends of the sleeve, said bore being reduced near the inner end of the sleeve to provide within the sleeve the annular stop shoulder 45 or abutment 21.

The other end of the bore is threaded to receive the plug 22. Plug 22 is adapted to hold within the sleeve, and adjust the tension of, the compression spring 23. The inner end of the 50 compression spring engages collar 24 formed on the end of the sliding bolt 25, that slides in the bore 20 of the sleeve. Spring 23, pressing against the collar 24, yieldably holds it against the stop 21.

Each sliding bolt 25 has formed therein the 55 annular groove 26. When collar 24 is in engage-

ment with shoulder 21, as shown in Fig. 4, the groove 26 is flush with the inner end of the sleeve 19, and is just barely visible in its entirety as readily noted from Figs. 1, 2, and 4.

The projecting or inner end of each bolt 25 is preferably formed with the enlarged head 27, each head adapted to engage one end of a roll of coins A.

Fixedly secured to each sleeve 19, and projecting through the longitudinal slot 14 of each casting, is the detent 28, adapted to be received in any of the transverse notches 15, 16, 17, 18.

The operation of the device may now be noted. Assuming that the device is, for example, going to be used to count and wrap dimes, the detents 28 will be positioned in the notches 15. This results in adjustment of the respective sleeves 19, and the bolts 25 carried thereby, as to the spacing therebetween, so that the heads 27 of the bolts are spaced apart a distance that will accommodate snugly a roll of fifty dimes. Once so adjusted, sleeves 19 will be held stationary, since longitudinal movement thereof will be prevented by positioning of the detents 28 in the transverse notches 15. Bolts 25 will of course be held yieldably the prescribed distance apart, by springs 23 pressing collars 24 against the stops or shoulders 21. The bolts 25 cannot be moved closer together, but either can of course be moved away from the other by yielding of the spring.

The user now simply takes a roll of dimes which he roughly estimates at fifty in number. If he has less than fifty, roll A will not fill the space between the heads 27. He therefore adds enough dimes to snugly fill the space.

If the roll contains more than fifty dimes, one or both annular grooves 26 will disappear from view. An appropriate number of dimes is accordingly removed from the roll until the grooves 26 are again visible.

It may be noted at this point that before even entering the roll A of dimes in groove 11, the user will first lay in said groove a coin wrapping paper, not shown.

The entire operation mentioned above is of course performed with great speed, and after a very little amount of practice, one using the machine is able to set up rolls of fifty dimes, ready for wrapping, in minimum time.

After the coins are counted as described above, one need only push the roll to the right in Fig. 1 or 2, so as to clear the left hand end of the roll for folding over a wrapper thereupon. The roll of coins is then pushed to the left for folding the right hand side of the wrapper over the right hand end of the roll. Bolts 25 yield in turn for performing this operation. Before performing this operation, the coins are rolled in the wrapper, preferably while still in center position as illustrated in Figs. 1 and 2, in which position the opposed heads 27 will hold the coins upright for easy rolling.

In Fig. 5, a modified form of the device has been illustrated. In this form, the coin holding bolt is designated 29, and is fixedly secured, and by integral formation to the enlarged cylindrical end portion 30, that is adjustably positioned in casing 13 by means of detent 31. In this form, the solid construction of bolt 29 and the end portion 30 takes the place of a bolt 25, spring 23, and sleeve 19. The form shown in Fig. 5 can be

substituted for the spring unit on either side of the device. The operation of the device remains the same, in that after the coins are counted, the coin holding bolt is moved outwardly, as for instance to the right. This provides ample room for folding the wrapping paper over the left end of the coin roll. Then, the roll of coins is pushed to the left in the groove so that the paper can be wrapped over the right end of the roll.

It will be readily noted that once the device is adjusted, the adjustment will be retained for the counting and wrapping of succeeding rolls. Assuming that all dimes have been counted, and that one desires next to count quarters, detents are moved to the notches 16, and the process repeated.

What is claimed is:

In a coin wrapping and counting machine a base having an elongated shallow groove opening 20 through the upper side thereof, elongated aligned tubular casings carried by the base adjacent opposite ends of the groove, said casings aligning longitudinally with the groove and having elongated longitudinal slots opening therethrough 25 adjacent the ends thereof remote from the groove, said tubular casings also having longitudinally spaced parallel peripheral notches extending therethrough and communicating with the longitudinal slots, elongated tubular sleeves 30 mounted in the tubular casings for longitudinal sliding movement therein, an inwardly extending annular stop shoulder carried by each sleeve adjacent the end thereof adjacent the groove, a plug carried by and closing the end of each 35 sleeve remote from its stop shoulder, a detent carried by each sleeve intermediate the ends thereof and extending radially therefrom through an adjacent longitudinal slot, said detents being adapted to engage the walls of selected peripheral 40 slots to hold the sleeves against longitudinal movement in their respective tubular casings, bolts mounted in the sleeves for longitudinal movement relative thereto, compression coiled springs within the sleeves and engaging the plugs 45 and bolts to yieldingly advance the bolts toward one another, outwardly extending annular stop collars carried by the bolts adjacent the ends thereof remote from the groove for engaging adjacent stop shoulders and limiting the advance 50 of the bolts under the influence of the springs, and signalling means carried by the bolts intermediate the ends thereof to visibly indicate that the bolts are fully advanced.
